UNITED STATES PATENT OFFICE.

JAMES H. SAGER, OF ROCHESTER, NEW YORK, ASSIGNOR, BY MESNE ASSIGNMENTS, TO THE SAGER MANUFACTURING COMPANY, OF SAME PLACE.

DESIGN FOR A TOE-CLIP FOR BICYCLES.

SPECIFICATION forming part of Design No. 24,158, dated March 26, 1895.

Application filed September 29, 1894. Serial No. 524,532. Term of patent 7 years.

To all whom it may concern:

Be it known that I, JAMES H. SAGER, a citizen of the United States, and a resident of the city of Rochester, in the county of Monroe and State of New York, have invented and produced a new and original Design for a Toe-Clip for Bicycles, of which the following is a specification, reference being had to the accompanying drawing thereof.

10 The drawing forming part of this specification is an isometric view of one of my toe clips.

15 My design consists in a metallic band A having the longitudinal slots a a' through the middle portion thereof and the perforations a^2 and a^3 adjacent to the ends thereof. The end A' is bent outwardly and substantially at right angles to the adjacent portion of the band. From the rectangular bend A^2 , the

band A continues substantially straight and then is bent back upon itself at A^3 in a curve substantially semi-circular. The band continues straight for a distance a little greater than the distance from the bend A^2 to the middle of the bend A^3 , and the end A^3 is then bent outward in a gentle curve and in the opposite direction to that of the end A^2 . The slots a and a' begin a short distance on each side of the middle of the bend A^3 and extend to near the bends A^4 and A^2 respectively. 30

What I claim is—

The design for a toe clip for bicycles, substantially as shown and described.

JAMES H. SAGER.
